(57) **CLAIM**

The ornamental design for a mat/tile module arrangement, as shown and described.

DESCRIPTION

FIG. 1 is a top view of a mat/tile arrangement showing my new design;

FIG. 2 is a side view of a portion of the mat/tile arrangement shown in FIG. 1;

FIG. 3 is a front view of the portion of the mat/tile arrangement shown in FIG. 2; and,

FIG. 4 is a perspective view of the portion of the mat/tile arrangement of FIG. 2.

The broken lines are provided for illustrative purposes only and form no part of the claimed design.
